CLAIM

The ornamental design for a bench for saunas as shown and described.

DESCRIPTION

Figure 2.1 is a perspective view of a bench for saunas, showing my new design;

The broken lines depict portions of the bench for saunas that form no part of the claimed design.

1 Claim, 7 Drawing Sheets
